tube for utilizing a third of the plurality of input signals.

In accordance with an important feature of the present invention, the latter means may comprise a cathode follower having an output circuit, and a feedback loop between this output circuit and the control electrode of the third vacuum tube may be provided, in order to maintain substantially constant the average amplitude of the third of the plurality of signals appearing across the output circuit of the cathode follower. This feedback loop may comprise a multivibrator having a triggering terminal and an output terminal. The triggering terminal may be coupled to the output circuit of the cathode follower and the output terminal of the multivibrator may be connected to a capacitor which is also included in circuit between the control electrode of the third vacuum tube and ground. In a preferred embodiment of the invention, the multivibrator is of the "one-shot" type.

By connecting a voltmeter or other suitable indicator across the above-mentioned capacitor, there is provided, in accordance with the present invention, means for accurately measuring the amplitude of short-duration pulses applied to the control electrode of the third vacuum tube.

The invention in another of its aspects relates to novel features of the instrumentalities described herein for achieving the principal objects of the invention and to novel principles employed in those instrumentalities, whether or not these features and principles are used for the above principal objects or in the stated field.

The above and other objects and features of the invention will be better understood by reference to the following description taken in connection with the accompanying drawings, in which like components are designated by like reference numerals and in which:

Fig. 1 is a schematic circuit diagram of the signal-combining arrangements in accordance with the present invention;

Fig. 2 shows graphically a composite wave appearing at the output of the circuit of Fig. 1; and

Fig. 3 is a schematic circuit diagram of the signal-separating arrangements in accordance with the present invention.

Referring to Fig. 1, there is shown a video amplifier comprising a first vacuum tube 1, the control electrode 2 of which is coupled by means of a capacitor 3 to the movable arm or slider 4 of a potentiometer 5 which in turn is connected between video signal input terminals 6 and 7. A resistor 8 is connected between control electrode 2 and ground. Cathode 9 of vacuum tube 1 is grounded through resistor 10. Screen-grid 11 is connected to a source of suitable positive potential diagrammatically illustrated at 12, and suppressor-grid 13 is grounded.

The anode 14 of vacuum tube 1 is connected through a resistor 15 and an inductor 16 to a source of suitable positive potential indicated at 17. Anode 14 is also coupled, by means of capacitor 18, to the control electrode 19 of second vacuum tube 20. A resistor 21 is connected between control electrode 19 and ground.

Cathode 22 of vacuum tube 20 is grounded through a resistor 23 shunted by a capacitor 24. The screen-grid 25 of vacuum tube 20 is connected to positive source 12, and the suppressor-grid 26 is grounded.

The anode 27 of vacuum tube 20 is connected through a resistor 28 and an inductor 29 to positive potential source 17. Anode 27 is also coupled,

by a capacitor 30, to the control electrode 31 of a vacuum tube 32. Control electrode 31 is connected through resistor 33 to the junction of series-connected resistors 34 and 35, which are connected as a voltage divider between potential source 17 and ground.

The cathode 36 of vacuum tube 32 is connected to ground through a potentiometer 37, the movable arm 38 of which is connected to an output terminal 39, the other output terminal 40 being grounded. The screen-grid 41 and the anode 42 of vacuum tube 32 are both connected to potential source 17. The suppressor-grid 43 of vacuum tube 32 is grounded.

Vacuum tube 44 has its cathode 45 connected to cathode 36 of vacuum tube 32. The control electrode 46 of vacuum tube 44 is connected to the movable arm 47 of a potentiometer 48, which in turn is connected in series with a resistor 49 between source 17 and ground. A capacitor 50 is connected between control electrode 46 and ground. The screen-grid 51 of vacuum tube 44 is connected to source 17, as is anode 52. The suppressor-grid 53 of vacuum tube 44 is grounded.

For the purpose of introducing trigger signals, a pair of terminals 54 and 55 are provided, the latter terminal being grounded. Terminal 54 is coupled by a capacitor 56 to the control electrode 57 of the left-hand portion of vacuum tube 58. A resistor 58 is connected between control electrode 57 and ground. The cathode 60 is grounded. The anode 61 is connected through a resistor 62 to source 17, and is coupled by a capacitor 63 to the cathode 64 of the right-hand portion of vacuum tube 58. Cathode 64 is connected to ground by a resistor 65. The control electrode 66 and the anode 67 of the right-hand portion of vacuum tube 58 are connected together and to cathode 9 of vacuum tube 1.

A pair of terminals 68 and 69 are provided for the purpose of introducing the azimuth signal input, terminal 69 being grounded. Terminal 68 is coupled by a capacitor 70 to the control electrode 71 of a vacuum tube 72, control electrode 71 being connected by a resistor 73 to a source of suitable negative potential indicated at 74. The cathode 75 is grounded, as is the suppressor-grid 76. The screen-grid 77 is connected to source 17. The anode 78 is connected through a resistor 79 to anode 27 of vacuum tube 20.

In operation, the positive video signals which are applied to input terminals 6 and 7 are amplified by vacuum tubes 1 and 20, the extent of this amplification being controllable by the setting of potentiometer 5. Inductors 16 and 29 in the anode circuits respectively of vacuum tubes 1 and 20 serve as peaking choke coils.

The positive trigger signals are applied to terminals 54 and 55 and are shaped by vacuum tube 58. The positive trigger signal voltages charge capacitor 56, and this charge leaks off exponentially through resistor 59. Thus a trigger pulse having a steep leading edge and a sloped trailing edge is developed across resistor 62 and applied to diode cathode 64 by means of capacitor 63. If desired, capacitor 63 may be made adjustable and used as a trigger signal gain control. The output of the trigger shaping circuit, which may for example comprise pulses having an amplitude of 40 volts, is mixed additively with the radar video signals in view of the connection from the diode anode (electrodes 66 and 67) to cathode 9 of vacuum tube 1. The right-hand portion of vacuum tube 58 serves as a diode rectifier to prevent any negative radar video signals,

which may be developed across resistor 10, from feeding back through the trigger shaping circuit.

The azimuth signal input is applied to terminals 68 and 69, and may comprise 150-volt positive pulses. Vacuum tube 72 is normally biased far below cut-off, since its control electrode 71 is connected to negative potential source 74 having for example, a potential of 105 volts. When the positive azimuth pulses are applied through capacitor 70 to control electrode 71, however, vacuum tube 72 becomes conductive and a large current flows through resistors 28 and 79 in its anode circuit. Since resistor 28 is common to the anode circuits of vacuum tubes 72 and 20, this large current flow through vacuum tube 72 causes anode 27 of vacuum tube 20 to change its potential with respect to ground in a negative direction. Its potential may, for example, become less positive by approximately 100 volts during each azimuth signal pulse.

The composite signal wave at the output of tube 20 is fed, by means of capacitor 30, to vacuum tube 32, which is arranged to operate as a cathode follower. Cathode 36 of this vacuum tube is normally positive with respect to ground, as for example by 25 volts. Since the azimuth pulses always cause at least 60-volt negative excursions of anode 27, even when the radar trigger and azimuth pulses are coincident, the azimuth pulses will drive control electrode 31 sufficiently negative with respect to cathode 36 to cut off vacuum tube 32. In this manner, the azimuth pulses take precedence over the video or trigger signals.

The output of cathode follower vacuum tube 32 is developed across potentiometer 37, and a desired portion of it is chosen by the setting of movable arm 38 and appears between output terminals 39 and 40.

Vacuum tube 44 serves as a clipper, and has its control electrode 46 maintained at a desired positive potential relative to ground depending upon the setting of sliding arm 47 of potentiometer 48. By suitably adjusting this positive potential, the extent of the negative excursions of cathode 45 due to the azimuth pulses may be limited to a desired value. Thus potentiometer 48 serves as an azimuth gain control.

The composite wave appearing at terminals 39 and 40 is illustrated in Fig. 2. It is seen to comprise positive radar video signals 80, negative azimuth pulses 81, and positive radar trigger signals 82. The relative amplitudes of these signals depends, of course, upon the settings of potentiometers 37 and 48, and upon the value of capacitor 63.

The composite output wave may be used to modulate a radio transmitter, or it may be sent directly to the receiving point by a suitable wire line or other conductive connection. Such intermediate link is not a part of the present invention.

Referring now to Fig. 3, which is a schematic circuit diagram of the signal-separating arrangements of the present invention, there is shown a video amplifier 100 having input terminals 101 and 102, the latter terminal being grounded. The ungrounded output terminal of video amplifier 100 is coupled by means of a capacitor 103 to the control electrode 104 of a vacuum tube 105. Control electrode 104 is connected by means of a resistor 106 to a source of negative potential 107 having, for example, a potential of three volts.

The cathode 108 of vacuum tube 105 is connected through a resistor 109 to a video output terminal 110. The other video output terminal 111 is grounded. A resistor 112 is connected between terminals 110 and 111.

The screen-grid 113 of vacuum tube 105 is connected to positive potential source 17. The suppressor-grid 114 is connected to cathode 108. The anode 115 is connected through a resistor 116 to positive potential source 17, and is coupled by means of capacitor 117 to the control electrode 118 of a vacuum tube 119. The resistor 120 is connected between control electrode 118 and ground.

15 The cathode 121 of vacuum tube 119 is grounded. The screen-grid 122 is connected to the junction of resistors 123 and 124 connected in series between positive potential source 17 and ground, and this electrode is by-passed to ground by a capacitor 125. The suppressor-grid 126 is grounded. The anode 127 is connected to an azimuth signal output terminal 128, the other azimuth signal output terminal 129 being grounded.

Cathode 108 of vacuum tube 105 is coupled by a capacitor 130 to the control electrode 131 of a vacuum tube 132. Resistors 133 and 134 are connected in series between control electrode 131 and negative potential source 74.

25 The cathode 135 of vacuum tube 132 is grounded, as is the suppressor-grid 136. The screen-grid 137 is connected to positive potential source 17. The anode 138 is connected to source 17 through a resistor 139, and is coupled by a capacitor 140 to the control electrode 141 of a vacuum tube 142. A resistor 143 is connected between control electrode 141 and ground. The cathode 144 is grounded, as is the suppressor-grid 145. Screen-grid 146 is connected by a resistor 147 to the junction of a resistor 148 and a capacitor 149 connected in series between potential source 17 and ground. The anode 150 is connected through an inductor 151 and a resistor 152 to the junction of resistors 147 and 148.

Anode 150 is coupled by a capacitor 153 to the control electrode 154 of the left-hand portion of a vacuum tube 155, a resistor 156 being connected between this control electrode and ground. The anode 157 is connected to positive potential source 17.

50 The cathode 158 of the left-hand portion of vacuum tube 155 is connected to ground through a resistor 159 and is coupled by a capacitor 160 to the control electrode 161 of a thyratron 162. Control electrode 161 is connected by a resistor 163 to the movable arm of a potentiometer 164, which in turn is connected in series with a resistor 165 between ground and negative potential source 74. The cathode 166 of thyratron 162 is connected to ground through a resistor 167, and

55 is directly connected to a trigger signal output terminal 168, the other trigger signal output terminal 169 being grounded. The anode 170 of thyratron 162 is connected through a resistor 171 to positive potential source 17. A series network comprising a resistor 172 and a capacitor 173 is connected between anode 170 and ground.

70 Cathode 158 of the left-hand portion of vacuum tube 155 is also coupled by a capacitor 174 to the control electrode 175 of the right-hand portion of vacuum tube 155. Control electrode 175 is connected to the junction of resistors 176 and 177 which are in turn connected in series between ground and negative potential source 74. The cathode 196 is grounded.

75 The anode 178 of the right-hand portion of

vacuum tube 155 is connected through a resistor 179 to positive potential source 17, and is coupled by a capacitor 180 to the control electrode 181 of the left-hand portion of a vacuum tube 182. A resistor 183 is connected between control electrode 181 and ground. The cathode 184 is grounded. The anode 185 is connected through a resistor 186 to positive potential source 17, and is also connected by a resistor 187 shunted by a capacitor 188 to the control electrode 189 of the right-hand portion of vacuum tube 182.

Control electrode 189 is connected by a resistor 190 to negative potential source 174. The cathode 191 is grounded. The anode 192 is connected to the junction of resistor 179 and capacitor 180. This junction is also connected by a resistor 193 to the junction of resistors 133 and 134, the latter junction being by-passed to ground by a capacitor 194. A voltmeter 195 may be connected between ground and the junction of resistors 133 and 134, as shown.

In operation, the input signal which is applied to terminals 101 and 102 comprises a composite wave having the general characteristics shown in Fig. 2. Since video amplifier 100 is assumed to have an even number of stages, a similar composite wave is applied to control electrode 104 of vacuum 105. This vacuum tube operates as a cathode follower, and its control electrode 104 has applied to it a suitable negative bias potential, as for example three volts. This bias serves to limit the azimuth pulses to a desired value, as for example 11 volts. The video signal output appears across resistor 112 in the cathode circuit of vacuum tube 105 and may be utilized at terminals 110 and 111.

Resistor 116 in the anode circuit of vacuum tube 105 has no appreciable effect upon the operation of this tube as a cathode follower since, the tube being a pentode, its anode current is determined largely by the potential applied to screen-grid 113. The negative azimuth pulses from video amplifier 100, however, cause the anode current of vacuum tube 105 to be cut off, thus producing positive excursions of anode 115 which may, for example, have a magnitude of approximately 20 volts. These positive anode excursions are applied to control electrode 118 of vacuum tube 119, which is so negatively biased by grid rectification action in the circuit of elements 117, 118 and 120 as to respond only to positive excursions. Such signals render the tube conductive, causing the azimuth pulse output to be developed between terminals 128 and 129.

The output of vacuum tube 105, as developed across its cathode resistors 109 and 112, is applied to control electrode 131 of vacuum tube 132, which functions as a trigger signal separator. Control electrode 131 is normally biased to a substantial negative value, as for example approximately 40 volts. This bias is sufficient to cut off the tube for peak values of the radar video signal. The azimuth signal pulses are of negative polarity and hence have no effect upon vacuum tube 132. The trigger signal pulses are positive and have approximately double the amplitude of the peak radar video signals. Thus each trigger pulse overcomes the normal negative bias on control electrode 131 and renders vacuum tube 132 conductive for the brief duration of each pulse.

The resultant negative anode swings are amplified by vacuum tube 142, which operates with zero bias on its control electrode 141. The purpose of series screen resistor 147 is to reduce the anode current of this vacuum tube to a reason-

able value. Each negative trigger pulse from vacuum tube 132 causes the anode current of vacuum tube 142 to be cut off. Inductor 151 in the anode circuit of this tube sharpens the resultant positive trigger pulses developed at anode 150. These pulses, which may for example have an amplitude of between 50 and 60 volts, are applied to control electrode 154 of the left-hand portion of vacuum tube 155, this tube portion functioning as a cathode follower and serving to provide an impedance step-down.

The positive trigger pulses developed across resistor 159 are applied to control electrode 161 of thyratron 162. This electrode is negatively biased by an amount depending upon the setting of potentiometer 164, so that the trigger pulses must exceed this bias potential in order to fire thyratron 162. Thus potentiometer 164 serves as a trigger sensitivity control. Resistor 172 limits the current flow through thyratron 162. The trigger pulses developed across resistor 167 may be utilized at trigger output terminals 168 and 169. These pulses for example may have a duration of 1 microsecond at 70 volts and one ampere.

For the purpose of maintaining the positive trigger pulses applied to control electrode 161 of thyratron 162 at a substantially constant level, a feedback loop is provided. The positive pulses developed across cathode resistor 159 associated with vacuum tube 155 are applied by means of capacitor 174 to control electrode 175 of the right-hand portion of vacuum tube 155. This electrode is normally held at a substantially negative potential, as for example approximately 66 volts, by the voltage divider comprising resistors 176 and 177. The right-hand portion of vacuum tube 155 conducts on each positive trigger pulse which exceeds this bias potential, and the resultant negative voltage swings of anode 178 are employed to trigger a "one-shot" multivibrator comprising vacuum tube 182. The left-hand portion of this vacuum tube is normally conducting so that its anode 185 has approximately the same potential as its control electrode 181. The right-hand portion of vacuum tube 182 is normally non-conducting.

When negative trigger pulses are received from vacuum tube 155, control electrode 181 is rendered increasingly negative so that the left-hand portion of vacuum tube 182 is cut off. The resultant positive swings of anode 185 are fed through resistor 187 shunted by capacitor 188 to control electrode 189 of the right-hand portion of vacuum tube 182, thereby rendering this electrode less negative and causing the right-hand portion of the tube to become conductive. Anode 192 thereupon becomes decreasingly positive, and this negative voltage swing is applied through an integrating network comprising resistors 193 and 194 and capacitor 194 to control electrode 131 of vacuum tube 132. Capacitor 194 is normally charged so that its ungrounded terminal is substantially negative with respect to ground, as for example by 40 volts. The negative voltage swings of anode 192 increase the negative voltage on capacitor 194 and thus increase the negative bias which is applied to control electrode 131 of vacuum tube 132.

Capacitor 194 is charged negatively at a slow exponential rate. This gradually increases the negative bias voltage on control electrode 131 of vacuum tube 132 until the pulse amplitude developed across cathode resistor 159 associated with vacuum tube 155 is reduced to a desired value, as for example to less than 50 to 60 volts. When this condition is reached, the multivibrator

comprising vacuum tube 182 rests until it is triggered by another pulse from anode 178 of vacuum tube 155. The charge and discharge of capacitor 194 occurs at a rate faster than the amplitude variation of the radar trigger pulses, but less rapidly than the pulse repetition rate. In this manner, the average pulse amplitude delivered at output terminals 168 and 169 remains essentially constant for a wide range of amplitudes for the input pulses applied by capacitor 130 to vacuum tube 132. The small departure from the average in the amplitude of individual pulses applied to control electrode 161 of thyratron 162, due to hunting action of the feedback circuit, is well within the firing range of the tube and hence introduces no difficulty.

As pointed out above, the negative charge on capacitor 194 increases as a function of the amplitude of the trigger signal pulses applied by capacitor 130 to control electrode 131 of vacuum tube 132. Although these input pulses are of extremely short duration, it is evident that the voltage across capacitor 194, as indicated for example by voltmeter 195, is closely proportional to the amplitude of the input pulses. This portion of the circuit, therefore, constitutes a very satisfactory means for measuring the amplitude of short-duration pulses, a measurement which has been difficult to make with previously known circuit arrangements.

While there has been described what is at present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A separating circuit comprising: a plurality of vacuum tubes, each having a cathode, an anode, and a control electrode; means for applying a composite wave comprising a plurality of signals upon the control electrode of a first of said vacuum tubes with respect to ground; a coupling between the anode of said first vacuum tube and the control electrode of a second of said vacuum tubes; means in the anode circuit of said second vacuum tube for utilizing a first of said signals; means in the cathode circuit of said first vacuum tube for utilizing a second of said signals; a coupling between the cathode of said first vacuum tube and the control electrode of a third of said vacuum tubes; means coupled to the anode of said third vacuum tube for utilizing a third of said signals, said means comprising a cathode follower having an output circuit; and means including a feedback loop between said output circuit and the control electrode of said third vacuum tube for maintaining the average amplitude of the third of said signals appearing across said output circuit substantially constant.

2. A separating circuit comprising: a plurality of vacuum tubes, each having a cathode, an anode, and a control electrode; means for applying a composite wave comprising a plurality of signals upon the control electrode of a first of said vacuum tubes with respect to ground; a coupling between the anode of said first vacuum tube and the control electrode of a second of said vacuum tubes; means in the anode circuit of said second vacuum tube for utilizing a first of said signals; means in the cathode circuit

of said first vacuum tube for utilizing a second of said signals; a coupling between the cathode of said first vacuum tube and the control electrode of a third of said vacuum tubes; means coupled to the anode of said third vacuum tube for utilizing a third of said signals, said means comprising a cathode follower having an output circuit; and a feedback loop between said output circuit and the control electrode of said third vacuum tube, said feedback loop comprising a single-stability multivibrator.

3. A regulated amplifier for providing output pulses of substantially constant amplitude from an input signal comprising pulses of widely varying amplitude, comprising: a vacuum tube having a cathode, an anode, and a control electrode; means for impressing said input signal between said control electrode and ground; a cathode follower having input and output electrodes, said input electrode being coupled to the output electrode of said vacuum tube; single-stability multivibrator having a triggering terminal and an output terminal; a coupling between said output electrode and said triggering terminal; a capacitor connected between said output terminal and ground; and a connection between said control electrode and the ungrounded terminal of said capacitor.

4. A regulated amplifier for providing output pulses of substantially constant amplitude from an input signal comprising pulses of widely varying amplitude, comprising: a vacuum tube having a cathode, an anode, and a control electrode; means for impressing said input signal between said control electrode and ground; a cathode follower having input and output electrodes, said input electrode being coupled to the output electrode of said vacuum tube; a multivibrator having a triggering terminal and an output terminal, said multivibrator being of the single-stability type; a coupling between said output electrode and said triggering terminal; a capacitor connected between said output terminal and ground; and a connection between said control electrode and the ungrounded terminal of said capacitor.

5. In combination, a composite wave sending system and a receiving system therefor, the sending system comprising: a first amplifier tube circuit receiving positive trigger pulses in its grid input circuit and producing amplified negative pulses in its plate output circuit, a second amplifying tube circuit receiving video input signals in its grid input circuit and producing an amplified and inverted version thereof in its plate output circuit, a rectifier coupling the plate output circuit of said first tube to the cathode of the second tube for causing high amplitude negative pulse voltage excursions of the plate voltage of said second tube greatly exceeding in magnitude the amplified versions of the video grid input voltage thereof, a third amplifier tube circuit receiving high amplitude positive pulses in its grid input circuit and producing high amplitude negative pulses in its plate circuit, and a fourth amplifier tube circuit having its plate coupled to the plate of said third tube and its grid input circuit coupled to the plate of the second tube, the fourth tube producing low amplitude positive output voltage variations corresponding to the positive video voltage variations in the input circuit of the second tube and also producing high amplitude positive pulses corresponding to the input pulses of the first tube, and these output components

being combined in the intercoupled plate circuits of the third and fourth tubes with the high amplitude negative pulses produced through the operation of the third tube; and said receiving system comprising: a first separator circuit tube having a control grid receiving a version of the composite wave of high amplitude positive trigger pulses, low amplitude video voltage variations, and high amplitude negative pulses, said first separator circuit tube having a cathode load output circuit and a plate output circuit, the plate output circuit supplying limited-amplitude sharp positive voltage excursions corresponding to the input of the third tube in the composite wave sending system and the cathode output circuit supplying sharp high amplitude positive voltage pulses corresponding to the trigger pulse input of the first tube in the composite wave sending system and also low amplitude video voltage variations, a second amplifier tube with its grid coupled to the plate circuit of said first separator circuit tube through a resistance-capacitance bias storage and coupling circuit providing a negative grid bias voltage to said second tube resulting from grid-rectification therein and limiting the output of the second tube to brief negative pulses corresponding only to the output of the third tube in the composite wave sending system, a third separator circuit tube having its grid circuit coupled to the cathode circuit of the first separator circuit tube, means supplying high voltage negative bias to the grid circuit of said third separator circuit tube, this voltage exceeding the sum of the cut-off bias of this tube and the positive peak values of the video voltage supplied through the cathode circuit of the first separator circuit tube whereby only the very high amplitude positive trigger pulses in the cathode circuit of said first separator circuit tube are sufficient to produce such changes of grid voltage in said third separator circuit tube as to produce plate current pulses therein, a two-stage amplifier coupled to the plate circuit of the third separator circuit tube, the output stage of the two-stage amplifier being a cathode follower stage for producing output voltage variations in the same sense as the input voltage variations in the input circuit of the third separator circuit tube, and hence for producing positive high amplitude pulses corresponding to the positive trigger pulses, a thyratron having a control grid coupled to the cathode follower output circuit of said two-stage amplifier to be fired recurrently by said amplified positive trigger pulses, the output circuit of the thyratron providing high power control current pulses timed according to said trigger pulses, and a feedback loop circuit between the output circuit of the two-stage amplifier and the grid bias circuit of said third separator circuit tube, said feedback loop circuit comprising a one-shot multivibrator including a normally conductive input tube portion with a grid circuit coupled to the output circuit of said two-stage amplifier and a normally non-conductive output tube circuit with its anode circuit coupled to the grid circuit of said third separator circuit tube, cross couplings being provided between the control grids and the anodes of the two tubes of the multivibrator, and a capacitor integrator connected in the output circuit of said multivibrator and the grid circuit of said third separator circuit tube for receiving current impulses from the output tube of said multivibrator corresponding to its pe-

riods of conductivity and supplementing the negative bias normally supplied to the control grid circuit of said third separator circuit tube by an amount variable automatically to suppress changes of output amplitude of said two-stage amplifier.

6. A composite wave sending system comprising a first amplifier tube circuit receiving positive trigger pulses in its grid input circuit and producing amplified negative pulses in its plate output circuit, a second amplifier tube circuit receiving video input signals in its grid input circuit and producing an amplified and inverted version thereof in its plate output circuit, 10 means connected between the plate output circuit of said first tube and the cathode of the second tube for causing high amplitude negative pulse voltage excursions of the plate voltage of said second tube greatly exceeding in magnitude the amplified versions of the video grid input voltage thereof, a third amplifier tube circuit receiving high amplitude positive pulses in its grid input circuit and producing high amplitude negative pulses in its plate circuit, 15 and a fourth amplifier tube circuit having its plate coupled to the plate of said third tube and its grid input circuit coupled to the plate of said second tube, the fourth tube producing low amplitude positive output voltage variations 20 corresponding to the positive video voltage variations in the input circuit of the second tube and also producing high amplitude positive pulses corresponding to the input pulses of the first tube, these output components being combined 25 in the intercoupled plate circuits of the third and fourth tubes with the high amplitude negative pulses produced by the third tube.
7. A composite wave sending system comprising a first amplifier tube circuit receiving positive trigger pulses in its grid input circuit and producing amplified negative pulses in its plate output circuit, a second amplifier tube circuit receiving input video signals in its grid input circuit and producing an amplified and inverted 30 version thereof in its plate output circuit, means including a rectifier coupling the plate output circuit of said first tube to the cathode of the second tube for causing high amplitude negative pulse voltage excursions of the plate voltage of said second tube greatly exceeding in magnitude the amplified versions of the video grid input voltage thereof, a third amplifier tube circuit receiving high amplitude positive pulses in its grid input circuit and producing high amplitude negative pulses in its plate circuit, and a fourth amplifier tube circuit having its plate 35 coupled to the plate of said third tube and its grid input circuit coupled to the plate of the second tube, the fourth tube producing low amplitude positive output voltage variations corresponding to the positive video voltage variations in the input circuit of the second tube and also producing high amplitude positive pulses corresponding to the input pulses of the first tube, these output components being combined in the 40 intercoupled plate circuits of the third and fourth tubes with the high amplitude negative pulses produced through the operation of the third tube.
8. Apparatus for combining three input signals to provide a composite transmission wave and for receiving said composite wave and separating it into three output signals respectively corresponding to said three input signals, the first and third input signals being distinct pulse

trains, comprising: first, second and third vacuum tubes; means for impressing the respective ones of said input signals upon the respective ones of said three vacuum tubes; means including a coupling between said first and second vacuum tubes for combining versions of the first and second of said input signals into a first composite signal with negative polarity high voltage pulses; a fourth vacuum tube; means including a coupling between the output circuits of said third vacuum tube and said fourth vacuum tube and a coupling between the output circuit of said second vacuum tube and the input circuit of said fourth vacuum tube for combining a version of said first composite signal with a version of said third input signal to provide the composite transmission wave; three separator circuit vacuum tubes; means for impressing said composite transmission wave upon a first of said separator circuit vacuum tubes, a coupling between said last-mentioned vacuum tube and a second of said separator circuit vacuum tubes; means associated with said last-mentioned vacuum tube for utilizing the output signals corresponding to the third input signal; means associated with said first separator circuit vacuum tube for utilizing the output signals corresponding to the second input signal; a coupling between said last-mentioned vacuum tube and the third separator circuit vacuum tube; means including an amplifier coupled to said last-mentioned vacuum tube for utilizing a third of said output signals; and means including a single-stability multivibrator and a voltage storage capacitor interposed between said third separator circuit vacuum tube and said amplifier for variably biasing said third separator circuit tube according to the output level of said amplifier, said multivibrator having its input circuit coupled to the output circuit of said amplifier and its output circuit con-

5 nected to said capacitor and to the grid circuit of said third separator circuit vacuum tube.
